UNITED STATES PATENT OFFICE

GEORGE B. RAYBURN, OF LOS ANGELES, CALIFORNIA

BATHER'S HAIR NET

Application filed July 25, 1930. Serial No. 470,746.

This invention appertains to improvements in hair nets and more particularly to a hair net especially adapted for use by bathers.

The principal object of the invention is to provide a hair net which will assume a compact unit when not in use, and in this respect is an improvement over my co-pending application, Serial No. 406,390, filed November 11, 1929, for bathing hair nets.

10 During the course of the following specification, other important objects and advantages will readily become apparent to the reader.

In the drawings:—

15 Figure 1 represents a plan view of the novel hair net.

Fig. 2 represents an edge elevation of the hair net.

Referring to the drawings wherein like numerals designate like parts, it can be seen that a continuous zig-zagged strip 5 is provided as a border, while an unit generally referred to by numeral 6 is located within the confines of the strip 5. This unit 6 is of sheet rubber or some other suitable elastic material as is the strip 5, and is cut to provide a multiplicity of spiral strips 7, extending from a central connecting portion 8, the outer ends of the strip 7 being connected to the strip 5 in the manner shown.

20 This bathing cap is to be constructed of a single sheet of elastic material stamped out by a preformed die, and as such, the strips 7 and 5 as well as the portions 8 are integral and of the same sheet of material.

While the foregoing specification sets forth the invention in definite terms, it is to be understood that numerous changes in the shape, size and materials may be resorted to, without departing from the spirit and scope of the invention as claimed hereinafter.

Having thus described my invention, what I claim as new is:—

25 1. A hair net comprising an annulus, a body for disposition within the annulus, said body being of elastic material and being divided to provide a plurality of spirally formed strips extending from the central portion of the body and connected at their ends to the said annulus.

2. A hair net comprising an elastically crimped annulus, a body for disposition within the annulus, said body being divided into a plurality of elongated strips extending from a solid central portion and connecting at their outer ends to the crimped annulus.

In testimony whereof I affix my signature.

GEORGE B. RAYBURN.
